GAS BURNER

Alvin G. Sherman, Grosse Pointe, Mich., assignor
to Sherman-Jackson-Roose Company, Detroit,
Mich., a corporation of Michigan

Application May 5, 1938, Serial No. 206,233

4 Claims. (Cl. 126—39)

This invention relates to gas burners and has particularly to do with the novel arrangement of a gas burner in a stove.

The present type of gas burners used especially on domestic gas ranges usually consist of a star shaped grate having holes in each prong of the star and positioned directly below a separate grate member which supports vessels being heated. One of the main objections to this old type of gas burner has been the unsightly appearance after the range has been in operation for a comparatively short time. The flame either impinges on, or comes in close contact with, the top grate prongs and causes the finish to be burned off so that the grates become unsightly in appearance. Also, the burner grates have been made, as a rule, from cast iron alone or cast iron with a porcelain surface, and have become heated to such an extent that any finish thereon soon deteriorated and caused the burners and grates to rust. Manufacturers have been unable to overcome these objections and consequently they have devised a coverall panel which is used to cover the burners when not in use.

With the previous stove designs, there has also been difficulty with what is called a "floating flame" which occurs when an oven is lighted which is below a burner on the top of the stove. This is caused by reason of the drafts from the oven which pass through the top burners causing the flame to actually lift from the burner. Previous constructions have also included a drip pan which extends below all of the two or four burners on a stove and which is of an ungainly size and consequently difficult to clean.

The burner is so constructed that it may be composed of aluminum, or ceramics which have been provided with glazed finishes. The burners are so constructed that an individual drip pan of convenient size may be removably located under each burner such that it may be removed at any time and washed along with the regular household utensils.

An object of the present invention is to provide a burner which is pleasing in appearance and which will remain so over a long period of use. Another object of the invention is to provide a burner which may be removed from the stove and washed simply by lifting it from its resting place. In present stove designs it is necessary to remove the top grate of the stove and go to considerable effort in removing the cast iron burners to clean them.

Another object of the present invention is to provide a burner which may be placed in its posi-

tion simply by lowering it into a burner socket. No special hangers are necessary. Additional objects of the invention have to do with a burner design in which there is no flame impingement on the grates and in which the burners are gas cooled so that metals and other materials with a low melting point may be used for the burner. Other features and objects of the invention have to do with the construction which eliminates lighter tubes, permits a very low simmering flame, and prevents a smothered flame and the resultant escape of unburned gases. The invention also contemplates a stove design in which there will be no floating of the top burner flames regardless of the operation of the oven. Other features and objects of the invention will be made clear in the following description.

In the drawings:

Fig. 1 is a perspective of a gas range showing two of the burners constructed in accordance with the present invention.

Fig. 2 is a section taken on the lines 2—2 of Fig. 1.

Fig. 3 is a section taken on the lines 3—3 of Fig. 1.

Figs. 4 and 5 are views taken on the lines 4—4 and 5—5, respectively, of Fig. 3.

Fig. 6 is a section taken on the line 6—6 of Fig. 5.

Fig. 7 is a section taken on the line 7—7 of Figs. 1 and 6.

Fig. 8 is a plan view of a modified form of burner especially adapted to be composed of ceramic material.

Fig. 9 is a transverse vertical section taken on the lines 9—9 of Fig. 8.

Fig. 10 is a horizontal section taken on the lines 10—10 of Fig. 9.

Fig. 11 is an illustration of the manner in which ceramic molding may be formed.

Figs. 12, 13 and 14 illustrate various views of a modification of a ceramic burner, the Fig. 14 being taken on the line 14—14 of Fig. 13.

Referring to Figs. 1 and 2, a stove top is shown at 15 as in a regular modern type of gas stove, and grates 16 are shown located in spaced relation in the stove top. Supported beneath the stove top is a draft tube or burner box housing 17 which extends from the back to the front of the stove and which is connected at the rear end to an air passageway 18. The front end of the draft tube 17 is closed. This draft tube 17 is preferably substantially semi-circular in cross section as shown in Fig. 3. A panel 19 represents the top of an oven which may be located in

the lower portion of the stove. By this arrangement oven draft will not affect the burners located in the top of the stove.

The details of the grates 16 and also of the entire burner arrangement are best shown in the vertical section of Fig. 3 and in the plan views of Figs. 4 and 5. Referring to Fig. 3, the gas supply pipe is shown at 20 and a pet-cock lever 21 admits gas to a pipe 22 which enters the lower portion of the draft tube 17. Projecting upwardly from the pipe 22 and from the lower portion of the tube 17 is an adjustable orifice unit 23 which serves as an inlet pipe. In the modification shown in Fig. 2, the burner consists of three cast or cored members, made preferably of aluminum, these being a top casting 16, forming the grate, a bottom casting 24, and a supply casting 25. The castings 16 and 24 are joined together to form a completed housing which is substantially hollow at all parts. The housing is formed as shown in the drawings with the supporting flange 26 and inwardly projecting burner members 27. The burner housing is entirely supported in the top panel of the stove in a manner which will be described with more detail later. The burner housings extend downwardly into the draft tube 17 in such a way that the mixing chamber of the burner is suspended near the bottom of the tube 17.

The various hollow passageways between the two castings 16 and 24 are connected by an outside annular passageway 28 which opens to the supply passageway 29 in the casting 25. Along the lower edge of the burner members 27 are provided outlet port holes 30 where the combustible gases are supplied to the flame. Directly above the rows of port holes 30, which extend in spaced relation around the burners 27, is a ledge 31 which overhangs the outlets of the holes 30. The port holes 30 are preferably drilled with a slight downward inclination from the inside to the outside. This permits a positioning of the ports closer to the utensil without "floating" and also prevents the flame from coming in close contact with the grate prongs. The ledge 31 above the flame ports serves as a gas duct when the burner is turned to a very low simmering flame. With this arrangement the ports will relight and consume all the gas even though the gas supply is insufficient to support the flame at all ports at once. Any gas escaping from an unlighted port will flow along the ledge 31 to a lighted port and the flame will then be carried to the unlighted port to consume the available gas. The ledge 31 also protects the burner ports 30 in case of spilling on the burner. The material spilled would tend to pass over the ports 30 and thus prevent clogging.

The top burner casting 16 is provided with upstanding ridges 32 and 33, as shown especially in Fig. 1. These ridges are provided to form supports for vessels being heated on the burner and to permit air to pass through the burner and under the vessel.

The gas supply casting 25 is formed in somewhat of an S-shape with a horizontal portion 25a, as shown in Fig. 3, so that it leads from the inlet pipe 23 at the center of the burner to the opening in the annular passageway 28. The lower end of the casting 25 is flared outwardly as at 34 to provide a mixing chamber 35 surrounding the inlet pipe 23. Adjustably fixed at the entrance of the chamber 35 is a plate 36 which is similar to the adjustment plates now used on gas stove burners.

Resting on the horizontal portion 25a of the casting 25 is a dish shaped drip pan and reflector plate 37 which is entirely supported by the casting 25 as will be seen from Figs. 3 and 4. The casting 25

is formed with outwardly extending horizontal prong members 38 which furnish adequate support for the drip pan 37 in conjunction with the horizontal portion 25a of the actual casting. The drip pan 37 is notched as at 39, so that it fits around the top vertical portion of the casting 25. A small recess is formed centrally in the lower surface of the drip pan and this recess is adapted to fit over a stud 40 formed centrally of the burner on the casting 25.

In the adjustment of this plate 36, a tool may be provided which will pass down through the burner, with pan 37 removed, and engage the plate 36 to permit adjustment while the burner is lighted.

Fastened to the bottom of the draft tube 17 and positioned around the inlet tube 23 is a metal stamping 41 having flared prongs 41a which serve to guide the lower portion 34 of the burner into position as the burner is lowered into place through the opening in the top of the stove. The stamping 41 is preferably fastened to the bottom of the draft tube by a bayonet slot arrangement so that it may be readily removed if desired. A flange or rim 34a on the mixing chamber serves to contact the prongs 41a and thus prevents disturbing of the adjustment of plate 36 on the mixing chamber. A lug 42 is formed on the burner casting 16 and adapted to engage a small hole beside the burner recess to position the burner as desired. Three or four embossed portions 42a are preferably provided around the burner opening in the top of the stove so that the top rim of the burner will be spaced slightly from the stove. This will permit air to pass through the spaces thus provided and will serve to cool the burner unit.

Since most modern stoves are equipped with a pilot tube and light it is necessary to provide the burner with a means for contacting said light. In most previous stoves it has been necessary to provide each burner with a tube which leads to the pilot light. With my type of burner the necessity for a tube is practically eliminated. As shown in Fig. 2, in a bank of two burners, a pilot light may be provided at the end of a tube 43 leading from the inlet pipe 20 to a point between the burners. This tube extends up between the burners which are equipped with a pilot transfer opening 44. This transfer opening is shown in detail in Figs. 5 and 6, where it will be seen that the lower casting 24 of the burner is provided with a slot 45 at one portion thereof, this slot being open to the annular recess 28 in the burner. When the inflammable gas is admitted to the burner by the opening of the valve, it will pass through the slot 45 and be exposed to the pilot light which will ignite the gas passing from the slot and readily pass the flame around to the regular burner openings 30. When a four burner cluster is used (not shown) only short tubes are necessary between the pilot light and the pilot transfer openings 45.

It will be seen that, since I have located the mixing chambers of each burner centrally thereof, they may be placed in any burner opening in the stove. By proper locating of the hole into which the lug 42 is projected, it is possible to locate each burner so that the pilot transfer opening will be properly positioned with respect to the pilot lights.

I have thus provided a unitary burner and grate which is pleasing in appearance and efficient in operation. Due to the fact that the ports 30 are under the ledge 31, they are practically

out of sight and since the flame from these ports impinges not on the grates, but directly on the cooking utensil, the burner will be extremely efficient in operation. Since the burner does not become unsightly after use, it is unnecessary to provide stoves with the covers lately used on gas ranges.

In old types of burners, especially those with a burner bowl and a burner unit located centrally thereof, combustion has been imperfect by reason of the fact that heat has been reflected downward from the pan being heated and has prevented the proper upward flow of secondary air between the inner aperture of the burner bowl and the burner unit. In my burner, as above described, the drip pan 37 serves also as a reflector plate. The heat radiated downward from the pan being heated is reflected by the pan 37 and, in addition, the secondary air flows undisturbed from the draft tube around the edges of the pan 37 to the burners. It will be noticed also that in my burner the outlet burner ports are always a fixed distance from the grates. With previous designs the burner unit has been supported independently by cross rods mounted below the grates and it has been difficult to keep these rods from sagging. Burner ports were often located at an improper distance from the grates. With my construction the entire unit is supported from the top of the stove. No cross bars are necessary and no adjusting is necessary as far as the vertical position of the burners is concerned.

Users of the ordinary gas burners sometimes remove the top grates when heating, for example, a wash boiler or other large vessel. When these grates are removed the passageways intended for escape of the products of combustion are closed and the result is a smothered burner with the possibility of escape of unburned gas. With my construction it is impossible to remove the supporting grate without removing the burner. Consequently the hazard of a smothered burner is removed.

In Figs. 8 to 14 I have shown various modifications of burners which are adapted for use with my invention. In Figs. 8, 9 and 10, a unitary construction burner is shown which is so designed that no separate and removable drip pan is necessary.

This burner may be formed of two castings, a top casting 46 and a base casting 47, the two being joined at 48. Referring to the cross section in Fig. 9, it will be seen that a mixing chamber 49 is provided which leads to an entrance passageway 50 connected with an annular passageway 51. Burner prongs 52 are provided, extending inwardly from the annular passageway 51 and having passageways 53 which lead to gas ports 54. The housing which lies below the annular passageway 51 and the burner units is a dish-shaped housing having side slots 55 through which secondary air may be furnished to the gas ports. Beneath each burner passageway 53 is a supporting wall structure which is provided with an opening 56 to facilitate the passage of air through the burners. Each burner prong is provided with top ridges 57 adapted to furnish support for cooking utensils resting on the burner and similarly, auxiliary ridges 58 are spaced between ridges 57.

It will be recognized that with the burner construction which I have shown it is possible to use materials which have, heretofore, been impractical for gas burners. For example, alumini-

num which has a fairly low melting point, may be used without a disintegration from heat since the burners are gas-cooled and there is no direct flame impingement. In addition, such refractory

- 5 materials as ceramic clay with a glazed finish, may be used and also white porcelain and glass, and such materials as are already common in the burner construction. It will be seen that the use of ceramic clay is particularly advantageous
 10 10 since the burners may be inexpensive and may be made without the use of cores by making the castings in two halves and placing the parts together before firing. The ports may be molded directly into the castings. Other advantages of
 15 15 ceramic burners is that when fired at, for example, 2700° F. to provide the proper glazed finish, they will be able to resist any heat to which they are subjected and remain with an attractive glossy finish. Also, these ceramic burners
 20 20 do not conduct heat to valves and gas cocks and consequently the operation of these cocks is not influenced by expanding and contracting. The ceramic burners may be made in various colors to match the general stove construction in which
 25 25 they are to be used.

In previous constructions the gas cocks used for regulating the supply of gas to burners have been located in such relation to the burners that heat has been conducted thereto. This necessitated making the cocks out of special materials to insure ease in operation regardless of temperature. In my design the gas cocks are located outside the burner box or draft tube 17 but within the stove. Consequently, heat does not pass readily to the gas cocks and they may be made with less expensive materials.

In Figs. 11, 12, 13, and 14, I have shown other modifications of my invention. Fig. 11, for example, shows a type of burner which is particularly adapted to ceramic construction since the holes may be molded therein and the burner may be formed of two molds which are placed together before firing, thus obviating the necessity of a core. In Fig. 12 I have shown a top burner grate 59 to be formed of ceramic material and glazed and adapted to be used with an ordinary type of burner bowl 60. It will be seen that the burner grate 59 is provided with inwardly extending fins 61 and 62 which furnish a support 50 for utensils being used over the gas fire.

What I claim is:

1. In a burner, an outer fuel passage in a main housing, combined grid and burner members on said housing projecting inwardly into the space enclosed by said housing, a supply housing connected with said main housing having a passageway joining said outer fuel passage, a removable pan adapted to lie under the opening in said housing, and means on said supply housing forming a support upon which said pan may rest in a substantially horizontal position where it will serve as a reflector plate and drip pan for said burner.

2. In a stove, a top panel having apertures 65 therein, a burner box housing below said top panel, a gas supply tube projecting vertically into said housing to a point spaced below an aperture in said top panel, a burner comprising a main housing having a fuel passage, and combined 70 grid and burner members projecting inwardly into the space enclosed by said main housing, a supply housing with one end connected with said main housing having a passageway joining said fuel passage and extending for a portion of its length 75 in a horizontal direction under said burner, and

a removable drip pan adapted to lie under the space enclosed by said burner housing and supported by the horizontal portion of said supply housing, a mixing chamber formed at the other end of said supply housing, and means on said burner box housing around said gas tube to guide said mixing chamber into position around said tube.

3. In a stove, a top panel having apertures therein, a burner box housing below said top panel, a gas supply tube projecting vertically into said housing to a point spaced below an aperture in said top panel, a burner comprising a main housing having a fuel passage, and combined grid and burner members projecting inwardly into the space enclosed by said main housing, a supply housing connected with said main housing having a passageway joining said fuel passage and extending for a portion of its length in a horizontal direction under said burner, and a removable drip pan adapted to lie under the space enclosed by said burner housing and supported by the horizontal portion of said supply housing, a mixing chamber, an adjusting plate fastened over said mixing chamber, means on said burner box housing for guiding said mixing chamber into place around said supply tube, and

means on said supply housing adjacent said adjusting plate to contact said guiding means and prevent contact with said adjusting plate.

4. In a stove, a top panel having apertures therein, a burner box housing below said top panel, a gas supply tube projecting vertically into said housing to a point spaced below an aperture in said top panel, a burner comprising a main housing having a fuel passage and combined grid and burner members projecting inwardly into the space enclosed by said housing, a supply housing connected at one end with said main housing having a passageway joining said fuel passage and extending for a portion of its length in a horizontal direction under said burner, and a removable drip pan adapted to lie under the space enclosed by said burner housing and supported by the horizontal portion of said supply housing, a mixing chamber formed at the other end of said supply housing and adapted to receive said supply tube, and means comprising flared prongs upstanding from a wall of said burner box housing around said tube for guiding the projecting end of said supply housing into place around said supply tube.

ALVIN G. SHERMAN.
